(57) **CLAIM**

The ornamental design for a laminar flow radial ceiling fan, as shown and described.

DESCRIPTION

FIG. 1 is a perspective view of laminar flow, radial ceiling fan disclosed in FIGS. 1-4;

FIG. 2 is a cross sectional side view of the circular, laminar flow, radial ceiling fan disclosed in FIG. 1 taken along section lines 2-2 in FIG. 1;

FIG. 3 is a reduced bottom plan view of the circular, laminar flow, radial ceiling fan of FIGS. 1 and 2; and,

FIG. 4 is a reduced top view of the circular, laminar flow, radial ceiling fan disclosed in FIGS. 1, 2 and 3.

The broken line showing of a drive motor is included for the purpose of illustrating environmental structure and forms no part of the claimed design.
